ATTORNEY

UNITED STATES PATENT OFFICE.

CHARLOTTE F. A. ROBB, OF BOSTON, MASSACHUSETTS.

LINGERIE CLASP.

Application filed July 6, 1925. Serial No. 41,737.

This invention relates to clasp devices and to a retaining clasp or lingerie straps and, more particularly, to a device which may be readily secured on the inner face of the shoulder portion of a dress and which will retain the straps of lingerie or under garments on the shoulders of the wearer and concealed under the dress.

When lingerie or under garments having shoulder straps are worn the straps have a tendency to fall off from the shoulders and interfere with the movements of the arms, and when worn under low necked or sleeveless dresses or waists become exposed and give an unsightly appearance. In order to insure the retention of the straps under the shoulders of the dress and on the shoulders of the wearer, it is necessary to secure the straps to the under surface of the dress in such a manner as to prevent their sidewise movement and with a securing means which is inconspicuous and readily mountable and removable from the dress and which will permit the straps to be easily secured and released.

An object of my present invention is to provide a metallic lingerie clasp of simple, unitary, structure, which may be readily and inconspicuously secured to the under seam of the shoulder of the dress and which will retain the lingerie straps on the shoulder concealed beneath the dress while otherwise permitting freedom of movement between the dress and the straps.

Another object of the invention is to provide a securing clasp for closing a retaining loop for shoulder straps which may be readily opened to receive or release the straps without danger of tearing the dress material and which may be readily closed.

Further objects of the invention are to provide a securing clasp which may be stamped from a single, integral, piece of metal; in which the pin element may be easily fitted so as to be securely retained; which will hold straps in a flat position; and which will present a smooth, flat, surface to the wearer.

With these and other objects in view, which will be more readily perceived from the following description, the invention com-

prises the device described and set forth in the following specification and claim.

The various features of the invention are illustrated in the accompanying drawings, 55 in which:

Fig. 1 is a perspective view of a clasp of a preferred form of my invention.

Fig. 2 is a plan view of the clasp.

Fig. 3 is a side view of the clasp.

1 indicates a flat piece of metal bent in a U shaped form. The upper portion of the U shaped form metal is bent to form a channel or a receiving recess 2.

The lower part of the U shaped member 1 has a lip 3 which fits into a channel 2. The upper part of the U shaped piece of metal has in it a number of holes 4, spaced proportionately apart so as to be able to be sewed in securely to the underside of the shoulders of the dress. The opening 5, which is made by this U shaped piece of metal, is for the purpose of permitting the shoulder straps of the wearer to be inserted therein so as to prevent the shoulder straps from moving about or being displaced from their position.

The clasp is sewed on to the under-side of the shoulders of the dress by means of openings 4. The straps are then slipped into the opening made by the bent U shaped 80 piece of metal. The lower part of the U shaped piece of metal is then secured into position so that lip 3 fits into the channel 2 and is kept there securely in position by means of the spring formed by the metallic 85 flat strip U.

Having described my invention, what I claim is:

A lingerie clasp comprising a U shaped member of spring metal, one side of said member having openings therein for the passage of stitching therethrough whereby the clasp may be secured to an article of wearing apparel, said side terminating in a bent-around loop constituting a spring abutment 95 and retaining means, the other side of said U shaped member having an off-set portion near its free end, said off-set portion terminating in a straight edge for cooperating with the end of said bent-around loop retaining means to releasably close the clasp.

CHARLOTTE F. A. ROBB.
